UNITED STATES PATENT OFFICE.

JOHN R. BELLIS, OF HACKETTSTOWN, NEW JERSEY.

DESIGN FOR A BUTTON.

55,018.

Specification for Design.

Patented May 4, 1920.

Application filed June 28, 1919. Serial No. 307,481. Term of patent 14 years.

To all whom it may concern:

Be it known that I, JOHN R. BELLIS, a citizen of the United States, and a resident of Hackettstown, in the county of Warren and State of New Jersey, have invented a new, original, and ornamental Design for a Button, of which the following is a specification.

Reference is to be had to the accompanying drawings in which—

Fig. 2 is an edge view thereof.

I claim—

The new and ornamental design for a button as shown.

JOHN R. BELLIS.
